CAN AND BOTTLE DISPOSAL

Harold J. Qualheim, 111 S. Vincennes Circle,
Racine, Wis.

Filed Nov. 20, 1959, Ser. No. 58,410

Term of patent 14 years

(Cl. D58—17)

The figure is a perspective view of a can and bottle disposal showing my new design.

The side not shown is the same as the side shown; the rear is flat and plain.

I claim:

The ornamental design for a can and bottle disposal, as shown and described.
